(57) **CLAIM**

The ornamental design for a display screen with icon, as shown and described.

DESCRIPTION

FIG. 1 is a close-up view of a display screen with icon showing our new design; and, FIG. 2 is a view of the display screen with icon of FIG. 1 shown on a mixing board. The broken line showings of the indicia within the boundaries of the claimed screen icon in both figures, and the remainder of the mixing board in FIG. 2 form no part of the claimed design. FIG. 2 depicts a sample environment for the display screen with icon of the claimed design.
